AUTOMATIC SEAR RELEASE FOR FIREARMS

Charles William Robbins, Cincinnati, Ohio

Application September 30, 1942, Serial No. 460,204

4 Claims. (Cl. 42—3)

1

The present invention relates to firearms, and more particularly to firearms of the so-called sub-machine gun type which are used by many, if not all of the up-to-date law enforcing agencies. These guns are usually of .45 calibre or larger, and are adapted to be fired at cyclic rates up to 800 shots per minute when operated full automatic.

In order that those persons whose duty it is to operate sub-machine guns may be adept at handling such weapons in times of emergency, it becomes imperative that such persons practice at frequent intervals for the purpose of mastering the characteristics of such guns, especially when fired full automatic. Unfortunately, practice periods, at most law enforcing agencies are not as frequent as desirable, first, because of the high cost of .45 calibre ammunition, and secondly, because of the danger inherent when firing such ammunition.

The primary object of the present invention is to provide means for converting a .45 calibre sub-machine gun for use with and operation on .22 calibre ammunition without sacrificing the major recoil and muzzle blast characteristics which are inherent with the use of .45 calibre ammunition.

Another object of the invention is to provide a .22 calibre conversion unit which is adapted to be quickly and easily interchanged with the firing mechanism of a larger calibre sub-machine gun.

Still another object of the invention is to provide simple, yet durable mechanical means for enabling a large calibre sub-machine gun to be fired single shot or full automatic on small calibre, inexpensive ammunition.

A further object of the invention is to provide means for exaggerating and multiplying the recoil incident to the firing of a .22 calibre cartridge so as to approach the recoil produced incident to the firing of a larger calibre cartridge.

Another object of the invention is to provide simple, yet highly effective means for automatically feeding .22 calibre ammunition to the hereinabove referred to conversion unit whereby the gun may be operated full automatic.

Still another object of the invention is to provide a conversion unit and a cartridge feeding device of the character hereinabove described, each of which are adapted to be operatively secured to the frame of a sub-machine gun without requiring the use of special tools or auxiliary holding devices.

These and other objects are attained by the

2

means described herein and disclosed in the accompanying drawings, in which:

Fig. 1 is a vertical central longitudinal section through a .45 calibre sub-machine gun of the Thompson type, showing one form of my .22 calibre adapter mechanism associated therewith, certain parts being shown in elevation for clarity of detail.

Fig. 2 is a vertical section through a large calibre sub-machine gun showing another form of .22 calibre adapter mechanism of the present invention, with the parts shown in fired position.

Fig. 3 is similar to Fig. 2, showing the parts in complete recoil and cocking position.

Fig. 4 is similar to Fig. 2, showing the parts in the primary cartridge stripping position immediately after the trigger had been pulled.

Fig. 5 is a side elevational view of a modified form of the adapter mechanism of Fig. 1 with the bolt in a fully extended position.

Fig. 6 is a top elevational view of the device of Fig. 5.

Fig. 7 is a perspective view of the bolt and firing pin which form a detail of the adapter mechanism disclosed in Figs. 5 and 6.

Fig. 8 is a side elevational view of the firing pin release mechanism of the adapter of Figs. 5 and 6.

Fig. 9 is a sectional view taken on line 9—9 of Fig. 6 showing the relationship of parts when the firing pin release mechanism is in a firing pin retaining position.

Fig. 10 is similar to Fig. 9 showing the relationship of the parts incident to tripping of the firing pin release mechanism.

Fig. 11 is a top elevational view of a modified form of adapter mechanism, comprising a detail of the present invention.

Fig. 12 is a perspective view of the bolt and firing pin of the adapter disclosed in Fig. 11.

Fig. 13 is a sectional view taken on line 13—13 of Fig. 11 showing the rotary bolt actuated firing pin lock in a firing pin retaining position.

Fig. 14 is a sectional view similar to Fig. 13 but showing the firing pin lock in a firing pin release position.

Fig. 15 is a sectional view of an insert barrel adapter comprising a detail of the invention.

Fig. 16 is a sectional view of a gas expansion nozzle which comprises a detail of the invention.

Fig. 17 is a side view of a cartridge magazine, partially in section, which comprises a detail of the invention.

Fig. 18 is a rear elevational view of the device of Fig. 17, but with the cartridges removed.

Fig. 19 is a top elevational view of the device of Fig. 18.

Fig. 20 is a sectional view taken on line 28—29 of Fig. 17 showing the relationship of a recoiling bolt relative to the uppermost cartridge and the magazine fingers.

In Fig. 1, a Thompson sub-machine gun is shown wherein the regular, or standard .45 calibre bolt (including the firing pin, hammer, extractor and hammer pin), actuator and recoil spring have been removed and replaced by my .22 calibre adapter.

As best disclosed in Figs. 2-4 inclusive, the .22 calibre adapter comprises, broadly speaking, the following elements: an insert barrel 38, a 15 bolt block 31, lock frame 32, recoil spring 33 for bolt block 31, hammer 36, hammer pin 37, hammer spring 38, hammer spring guide 39, combination spacer block and spring guide 35, sear 45, and a .22 calibre cartridge magazine 46.

Insert barrel 38 may be bodily introduced into the regular barrel 47 of the gun from the rear or breech end. The insert barrel may include a rifled portion 48, an enlarged bolt receiving portion or firing chamber 49 and an enlarged abutment 50 which is adapted to engage face 300 of the standard or large calibre firing chamber provided in the gun receiver 54 thereby locating the insert barrel relative to the regular barrel 47. It will be observed that the forward end 51 of the insert barrel terminates short of the end 52 of the regular barrel by a dimension indicated by the letter X. The insert barrel may be held in place by engagement with a spacer block 53 secured to and carried by the forward end of lock frame 32 which lock frame is adapted to be inserted upwardly into the receiver 54 and then pushed forward until corresponding mating members on the insert barrel abutment 50 and the lock frame block 53 engage one another. When such an engagement has been effected, the insert barrel has been properly and automatically aligned relative to regular barrel 47.

The lock frame 32, which comprises a pair of laterally spaced side plates 320 interconnected at their forward ends by spacer block 53 may be held in place against the forward wall 55 of the receiver by means of a spacer block 35 formed of any suitable material adapted to withstand the shock of recoil which occurs incident to firing of the gun. If desired, the spacer block 35 may be provided with a pair of spring receptive chambers 56 and 57 for aligning recoil spring 33 and hammer spring 38 relative to bolt 31 and hammer 36 respectively whereby the springs will normally urge the bolt and hammer forwardly, that is, to the right, toward front wall 55 of the receiver. At this point it should be observed that no special tools are required when inserting my adapter device into the receiver of a large calibre sub-machine gun. After the .22 calibre adapter has thus been located in the receiver, the gun frame 58 may be secured in place thereby fastening the lock frame 32 and spacer block 35 within receiver 54.

With particular reference now to Figs. 2, 3 and 4, it will be observed that bolt block 31 comprises a forwardly extending bolt portion 59, a rearwardly extending portion 60, and an intermediate portion 61 disposed at substantially right angles to portions 59 and 60. The upper end of intermediate portion 61 may be provided with and terminate in a cocking knob 62. The lower face of the bolt 59 is preferably cut away as at 63 whereby to provide a stripping lug 42 which

is adapted to engage the upper rear edge of the rim 65 of a cartridge 64 positioned between the upstanding fingers of cartridge magazine 46.

The hammer pin 37 extends through a hole 68 in bolt 59, said hammer pin adapted for reciprocatory movement relative to the bolt. The opposite end of the hammer pin terminates at and is secured to hammer 36, by any convenient means. In the adapter unit disclosed in Figs. 2, 3 and 4, hammer 36 is provided with a sear lug 69 having an upright face 70 and an inclined face 71, as illustrated. Sear 45 may be pivotally mounted to a side wall 320 of the lock frame 32 by means of a pivot pin 72. The sear comprises a short upper leg 73 and a longer lower leg 74, the free end of the upper leg being provided with a sear lug engaging face 75 and the free end of lower leg is provided with a bolt lug engaging face 76, which is adapted to engage bolt lug 66 which is carried by and secured to the rear end of portion 60 of bolt block 31. Sear 45 is normally urged in a clockwise direction about pivot pin 72 by means of a suitable spring member such as 77 which may be mounted on pins 78 and 79 carried by a side wall of the lock frame. The free outer end 80 of the spring is adapted to engage notch 81 of the sear.

It should be understood that the sear is fixed relative to lock frame 32, whereas the bolt block 31 and hammer 36 are adapted for reciprocatory movement relative to the sear and lock frame.

With reference now to Fig. 3, it will be observed that face 75 of upper sear leg 73 is adapted to engage upright face 70 of sear lug 69 of the hammer 36, thereby restraining the hammer against forward movement, to the right, in response to the action of spring 38, for maintaining the hammer in a fully cocked position. It will be observed that when the bolt block 31 has been moved rearwardly against spring 33 to a full retracted position, member 60 of the bolt block extends under and to the rear of the sear, and the bolt lug 66 is spaced from and to the rear of face 76 of lower leg 74 of the sear.

45 The hammer is adapted to be released or tripped from the cocked position disclosed in Fig. 3 when bolt lug 66 strikes face 76 of lower leg 74 of the sear as the bolt block 31 is moved forwardly, to the right, by spring 33. The impact imparted to the sear by the bolt lug 66 moves the sear in a counterclockwise direction about pivot pin 72 and against the counteraction of spring 77 for disengaging face 75 of the sear from forward face 70 of sear lug 69, thereby permitting the hammer to be shot forwardly, to the right, to the position disclosed in Fig. 2, under the influence of spring 38.

At this point it should be observed that bolt 59 is adapted to reciprocate within chamber 49 of the insert barrel 38, the forward limit of bolt travel relative to chamber 49 being determined by shoulder 83, the rearward limit of bolt travel being determined by the characteristics of spring 33. With reference now to Fig. 3, it will be observed that when the bolt block has been fully retracted, cartridge 64 is urged upwardly by means of mechanism housed within magazine 46, which will be described in detail later, to present cartridge rim or base 65 to be engaged by stripping lug 42 incident to forward movement, to the right, of the bolt. As the bolt moves to the right, cartridge 64 is stripped, or transferred from the magazine to firing chamber 49, whereby cartridge base 65 will be lodged between shoulder 75 83 of the insert barrel and forward face 24 of

the bolt. The physical relationship of the bolt, hammer, sear, and bolt lug are such that the hammer will be released from the full cocked position disclosed in Figs. 3 and 4 concurrently with, or a split second before, the bolt reaches the end of its forward travel for positioning the cartridge base 65 between the forward face 84 of the bolt and shoulder 83 of chamber 49, whereby the cartridge will be discharged at the proper moment. When the cartridge has been discharged its projectile 66 will be shot forwardly, to the right, through rifled portion 48 of the barrel by the force of the expanding gas 87 generated incident to the firing of the powder charge of the cartridge. Gas 87 not only pushes the projectile forwardly through the barrel, to the right, but it likewise acts upon cartridge case 85, pushing it rearwardly, to the left, against face 84 of bolt 59 with such force as to move the entire bolt block and hammer assembly rearwardly, to the left, against the counterforce of springs 33 and 38 for effecting a complete recoil of the bolt to the position disclosed in Fig. 3. The cartridge case 85 may be ejected by means of an ejector 88, which may, if desired, be mounted on magazine 46 as hereinafter more fully explained. The recoil of the bolt block and hammer assembly will continue after cartridge case 85 has been thus ejected from barrel chamber 49. As the bolt block and hammer assembly are thus moved rearwardly, to the left, short leg 73 of the sear will engage inclined face 71 of the sear lug for turning the sear in a counterclockwise direction incident to which face 75 of the sear will become engaged with face 70 of sear lug 69 for establishing the relationship of parts disclosed in Fig. 3.

Unless the regular gun sear, not illustrated, is permitted to engage the sear notch 89 provided in portion 60 of the bolt block, the gun will continue to operate fully automatic, firing cartridge after cartridge until the supply has been exhausted. However, if it becomes necessary or desirable to operate the gun single shot, this may be done by permitting the gun sear to engage notch 89 for releasably maintaining or locking the parts in the relative positions disclosed in Fig. 3.

In Figs. 5 and 6, a modified form of adapter unit is disclosed, said unit comprising a lock frame 321 having a pair of spaced side walls 90 and 91, a rear wall 92 and a forward lock frame block 53. The bolt block and hammer assembly disclosed in Fig. 7 is adapted to be inserted between walls 90 and 91, said walls acting as guides for directing the reciprocation of the bolt and hammer. The primary distinction between the adapter disclosed in Figs. 5 and 6 and that disclosed in Figs. 2 to 4 inclusive resides in the modified form of cocking knob 620 and in the structural details of the means used to releasably maintain hammer 36 in a cocked position, and in the structural details of the means utilized for tripping the hammer as the bolt block is shot forwardly, to the right, by means of recoil spring 33. If desired a hammer spring guide 39 may be provided, as illustrated. With reference now to Figs. 6 and 7, it will be observed that hammer 36 includes a rearwardly projecting hammer limb or member 93 the free outer edge of which terminates in an upturned lip 94 which is adapted to be releasably engaged by a complementary depending latch member 95 of sear 96 pivotally mounted on a pivot pin 97 secured between and carried by walls 90 and 91. The sear is normally

urged in a clockwise direction about pivot pin 97 by means of spring 98. Sear 96 is adapted to be moved in a counterclockwise direction about pivot pin 97 for effecting a disengagement of latch member 95 from upturned lip 94 of hammer limb 93 by means of a sear trip member 99 mounted for reciprocatory motion on a track undercut in side wall 91 of lock frame 321, see Figs. 9 and 10, which includes a ramp 100 which is complementary to inclined face 101 of depending leg 102 of the sear 96, see Fig. 8. The sear trip member likewise includes a stop pin 103 at its rear end and a stop pin 200 at its front end, which pins are adapted to be engaged by bolt lug 66 of the bolt block as said bolt block reaches the end of its rearward and forward strokes respectively. When the bolt block is shot forwardly, to the right, by the recoil spring 33, it strikes pin 200 thereby shifting the sear trip member 99 to the right for effecting engagement of ramp 100 with inclined face 101 for lifting latch member 95 thereby releasing the hammer to a firing position. As the bolt block moves rearwardly it will engage and move hammer 36 rearwardly to a retracted sear engaging position, and lug 66 will engage pin 103 for shifting the sear trip member 99 to the left. The numeral 201 indicates a notch into which a standard extractor unit may be inserted, in those instances where the use of such a device is desired. As illustrated, hammer 36 is slidably supported upon and carried by the rearwardly projecting portion 60 of the bolt block.

In Figs. 9 and 10 the relationship of the sear and the sear trip member is disclosed showing the sear in hammer cocked and hammer released positions respectively.

The adapter disclosed in Fig. 11 embodies a rotary sear 104 in lieu of the pivoted sears disclosed in Figs. 2, 3, 4, 6, 8, 9 and 10. With particular reference to Fig. 11, it will be observed that the rotary sear member 104 includes a tubular portion 105 one end of which terminates in an enlarged collar member 106 which is provided with a tapered sear notch 107. Tubular portion 105 may be mounted for rotary motion around a shaft-like member 108 which may be formed as an integral part of the rear wall of the lock frame 321, which comprises a pair of spaced side walls 900 and 910, and forward lock frame block 53. Shaft-like member 108 is preferably hollow to provide a spring receptive chamber 157 into which hammer spring 38 extends.

As disclosed in Fig. 12, hammer 36 includes a rearwardly extending arm or hammer branch 109 which terminates in an out-turned lip 110 which is adapted to engage the tapered sear notch 107. Sear 104 is adapted to be rocked or rotated about shaft 108 by means of a bolt abutment member 111 provided on bolt block 31 as illustrated. As disclosed in Figs. 13 and 14, collar member 106 is provided with a flattened cam follower surface 112 which is adapted to be engaged by bolt abutment member 111 for rocking or rotating sear 104 about shaft 108. The sear is normally urged in a counterclockwise direction by means of a spring 113, or the like, for positioning the tapered sear notch 107 to engage lip 110 of the hammer. A spacer block 350 may be located between the rear wall of lock frame 321 and the rear wall of the receiver.

In operation, the hammer 36 will be retained in a retracted, cocked position by sear 104 until such time as bolt abutment member 111 is caused to pass under flattened surface 112 for rotating the sear from the position disclosed in Fig. 13 to

that disclosed in Fig. 14. It will be understood that the longitudinal path of bolt abutment member 111 is so related to sear 104 as to be disposed on one side or the other of a vertical through the center of shaft 108 to provide a rocking or rotating motion to the sear against the counter-force of spring 113 as the abutment member is caused to travel beneath flattened surface 112.

The adapter unit disclosed in Fig. 1 differs from that disclosed in Figs. 5 to 10 inclusive primarily in that bolt lug 66 is adapted to move longitudinally between a pair of spaced lugs 114 and 115 provided at the front and rear ends of a sear trip member 116 which is mounted for limited longitudinal motion on pins 117 which cooperate with elongated slots 118 provided in the body of the trip member. A ramp 119 is provided as shown for cooperation with inclined face 120 of sear 121. Sear 121 is pivotally mounted about pivot pin 122, and is urged in a clockwise direction by means of spring 123 whereby sear latch member 95 is normally urged to engage slot 124 of hammer 36.

It will be observed that a different type of insert barrel is disclosed in Fig. 1 than is disclosed in Figs. 2 to 4 inclusive. The insert barrel of Figs. 2 to 4 inclusive is what will hereinafter be referred to as a short insert barrel 31, the end 51 of which terminates from the end 52 of the sub-machine gun barrel by a dimension indicated by the letter X. The short insert barrel, as has already been explained, is inserted into the larger calibre barrel of the gun from the rear thereof, and that portion of the regular gun barrel beyond the end of the insert barrel functions as an auxiliary expansion chamber for imparting a lift or upward kick to the gun barrel each time a cartridge is fired.

In those instances where it is desirable to obtain maximum accuracy of the .22 calibre projectile, the so-called long insert barrel 131 disclosed in Fig. 1 may be used. The forward end of the barrel may be provided with external threads 125 and the rear end may be provided with external threads 126. The barrel is adapted to be inserted through the large calibre gun barrel from the front, being held in place by the threaded engagement of external threads 125 with complementary internal threads 127 provided at the forward end of an insert barrel stub 128 which may be formed as an integral part of the lock frame 32, or which may be provided in the forward edge of a separate sub-barrel insert piece 82 disclosed in Fig. 15, the overall length of which, denoted by the letter Z, corresponds with the length of the regular short insert barrel 31 disclosed in Figs. 2-4, measured from rear face 129 to shoulder 130. In those instances where the sub-barrel 82 is used, the same adapter unit may be employed for use with a short insert barrel 31 or a long insert barrel 131.

With reference to Fig. 1, it will be observed that external threads 125 are disposed beyond forward end 52 of the large calibre barrel 47. Such an arrangement is desirable in order that an expansion chamber or nozzle 132 of the general type disclosed in Fig. 16 may be associated with a long insert barrel for emphasizing the recoil and barrel lift characteristics of the gun when it is operated on .22 calibre ammunition, and whereby such characteristics will approach those inherent when the gun is operated on .45 calibre ammunition.

The expansion nozzle may be provided with internal threads 133 which are adapted to en-

gage threads 125 of the long insert barrel. An opening 134 is provided in the forward end of the nozzle, said opening being of a dimension sufficient to facilitate the passage of a .22 calibre projectile therethrough. The inner face 135 of the nozzle between threads 133 and opening 134 is preferably tapered toward the opening as illustrated. If desired, a plurality of vent holes indicated by the numeral 136 may be provided for the purpose of permitting the high pressure gases of combustion to be vented downwardly therethrough for effecting an upward reaction to the end of the gun.

Unlike ammunition of .45 calibre and larger in which the cartridge bases are of substantially the same diameter as the cartridge cases, the bases of .22 calibre rimfire cartridges are appreciably larger in diameter than their respective casings, thereby rendering impractical those types of cartridge magazines customarily used with the larger calibre ammunition. When .22 calibre rimfire cartridges are stacked one upon another, they will assume the relationship disclosed in Fig. 17, wherein each succeedingly lower cartridge is disposed at a greater inclination than the one immediately preceding it. The forward edges 136 of projectiles 86 form an arc, when their bases or rims are disposed in contact with a vertical wall such as 137 of the magazine, said arc being directly proportional to the number of cartridges stacked. In order that each cartridge may be properly presented to stripping lips 138 and 139, a special cartridge feeding platform has been provided.

With reference to Figs. 17 and 18 it will be observed that magazine 46 may comprise a pair of spaced rear and front walls 137 and 140, a pair of spaced side walls 141 and 142 and a bottom 143. The lateral distance between front and rear walls 140 and 137 is of a dimension somewhat greater than the overall length of a .22 calibre cartridge, and the lateral distance between side walls 141 and 142 may be of a dimension somewhat larger than the diameter of base 65 of a cartridge, see Fig. 20. A follower 144 having such a contour and dimensions as to slidably engage front and rear walls 140 and 137 and side walls 141 and 142, may be provided. Suitable means such as a follower spring 145 may be interposed between bottom wall 143 and the follower for normally urging the follower upwardly toward the stripping lips. A platform 146 may be pivotally secured to follower 144 about pivot pin 147. The free outer edge 148 of the platform may be normally urged downwardly by means of a spring 149, the lower end of said spring being anchored to follower 144, by any appropriate means. A vertical guide edge 150 which conforms in contour with the arc described by the forward edges 136 of projectiles 86 may be provided in one or both of side walls 141 and 142. A follower pin 151 is carried by platform 146, said pin being rigidly secured to the platform and adapted to abut against arcuate guide edge 150. It will be observed that as follower 144 moves upwardly under the influence of spring 145, platform 146 will be moved in a clockwise direction about pivot pin 147, as said platform approaches a horizontal plane. The angle of inclination of the platform is at all times dependent upon the relative location of follower 144, whereby the angle of lift of platform 146 will automatically be adjusted to compensate for the inclination of the cartridges as they are intermittently presented to the stripping lips. In this manner it is possible to effectively

feed .22 calibre rimfire cartridges at a rate of speed sufficient to permit a sub-machine gun to operate at cyclic rates up to 800 shots per minute, without jamming the cartridges. If desired, a lug 152 may be formed integrally with follower 144, and projected outwardly through a vertical slot 153 provided in rear wall 137. Lug 152 is adapted to operate a device provided on most regular .45 calibre sub-machine guns for the purpose of locking the bolt in an open position after the last cartridge of the magazine has been fired. A pair of outwardly projecting finger grip members 154 and 155 may be secured to follower 144 for enabling the follower to be retracted against the counterforce of spring 145 during the insertion of ammunition into the magazine.

Stripping lips 138 and 139 are designed to resiliently retain the uppermost cartridge in alignment with stripping lug 42 of bolt 59, whereby the uppermost cartridge cannot be accidentally or unintentionally dislodged from the magazine. In Fig. 20 the parts are shown in position as the bolt is moving backward, to the left, in recoil, it being understood that as soon as stripping lug 42 is moved back far enough to clear cartridge base or rim 65 that the uppermost cartridge will be lifted vertically by spring 145 whereby the stripping lips will engage the cartridge case 25. When thus engaged rim 65 projects a substantial distance above the upper edge of stripping fingers 138 and 139 and in line with stripping lug 42 of the bolt. An ejector 88 may be suitably secured to side wall 142 of the magazine, said ejector including a cartridge base engaging finger 156 against which the rear face of a cartridge base is adapted to strike incident to the rearward travel of an empty cartridge case by the back pressure generated incident to the firing of a cartridge, as has already been explained.

It should be understood that the upper portion of magazine 46 is adapted to be inserted upwardly through an opening 257 provided in the lower wall of the chamber 49 of the insert barrels, whereby cartridges may be fed directly from the stripping lips of the magazine into the rear end of an insert barrel. The regular .45 cartridge ramp, indicated in Figs. 1 to 4 inclusive by the numeral 158, is not used.

The magazine may be secured to the gun frame in the same manner and using the same magazine mounting means as are used when a regular large calibre ammunition magazine is mounted to the gun frame.

It should be understood that the frame includes a hand grip portion 301, a trigger 302, a suitable trigger mechanism, not illustrated, located in housing 303, see Fig. 1. Trigger 302 may be utilized for actuating a sear not shown, which may engage sear notch 69 of the rearward extending bolt block 60 for controlling the firing cycle on the gun.

In those instances where the large calibre regular barrel 47 of a machine gun is provided with a Cutts compensator device, the effect of such a device may be nullified by using a long insert barrel, such as 131, the length of which is of such a dimension as to locate the externally threaded portion 125 beyond the end of the Cutts compensator, whereby the effect of the compensator will be nullified and an expansion chamber 132 may be mounted on the insert barrel for exaggerating the recoil and barrel lift characteristics of the gun.

It should be understood that various modifications and changes in the structural details of the

device may be made, such as making spacer block 35 an integral part of the lock frame, within the scope of the appended claims, without departing from the spirit of the invention.

5 I claim:

1. In an automatic firearm, a breech chamber, a bolt block positioned in and mounted for reciprocation longitudinally of said chamber, a hammer mounted for reciprocation on and longitudinally of said bolt block, means to guide said bolt block and hammer during their reciprocatory movements, resilient means normally urging said bolt block and said hammer toward a forward projected position, said hammer provided with a rearwardly extending limb terminating in a catch member, a bearing shaft in and extending longitudinally of the breech chamber, a sear rotatably mounted on said bearing shaft, said sear being positioned above the bolt block and provided with a latch member for releasably engaging said hammer limb catch member, resilient means normally rotating and holding said sear to a catch engaging position in respect to said hammer limb catch member, a cam follower on said sear, means carried by the bolt block constructed and arranged to engage said cam follower as the bolt block approaches a forward projected position, and said last named bolt block carried means operating to rotate said sear and release the latch member thereof from engagement with the catch member of the hammer limb.

2. In an automatic firearm, a breech chamber, a bolt block positioned in and mounted for reciprocation longitudinally of said chamber, a hammer mounted for reciprocation on and longitudinally of said bolt block, means to guide said bolt block and hammer during their reciprocatory movements, resilient means normally urging said bolt block and said hammer toward a forward projected position, said hammer provided with a rearwardly extending limb terminating in a catch member, a bearing shaft in and extending longitudinally of the breech chamber, a tubular sear rotatably mounted on said bearing shaft, said sear including an annular collar having a cut-out portion providing a latch member constructed and arranged to releasably engage said hammer limb catch member, resilient means normally rotating and holding said sear to a catch engaging position in respect to said hammer limb catch member, a cam surface on said sear collar, means carried by the bolt block constructed and arranged to engage said sear collar cam surface as the bolt block approaches a forward projected position, and said last named bolt block carried means operating to rotate said sear and release the latch member thereof from engagement with the catch member of the hammer limb.

3. A construction as defined in claim 2 wherein, the resilient means normally urging the hammer toward a forward projected position extends from the hammer to and in engagement with an abutment at the rear end of the breech chamber, and said sear bearing shaft being hollow for the passage of said resilient means therethrough.

4. In an automatic firearm, a breech chamber, a bolt block positioned in and mounted for reciprocation longitudinally of said chamber, a hammer mounted for reciprocation on and longitudinally of said bolt block, means to guide said bolt block and hammer during their reciprocatory movements, resilient means normally urging said bolt block and said hammer toward a forward projected position, said hammer provided with a

rearwardly extending limb terminating in a catch member, a bearing shaft in and extending longitudinally of the breech chamber, a sear rotatably mounted on said bearing shaft, said sear having a collar-like portion extending transverse said breech chamber and provided with a cut-out portion for the passage of the hammer limb and its catch member to provide a latch for releasably engaging said hammer limb catch member, resilient means normally rotating and holding said sear to a catch engaging position in respect to said hammer limb catch member, one face of the cut-out portion of said sear collar-like member being beveled and said hammer limb provided with a beveled portion constructed and arranged to engage the beveled portion of the sear to cause rotation of the sear to permit the passage therethrough of the hammer limb and its catch member when the hammer is moved to a retracted position, a cam surface on said sear, means carried by the bolt block constructed and arranged to engage said sear cam surface as the bolt block approaches a forward projected position, and said last named bolt block carried means operating to rotate said sear and release the catch member thereof from engagement with the catch member of the hammer limb.

CHARLES WILLIAM ROBBINS.
